UNITED STATES PATENT OFFICE.

THOMAS F. HANWAY, OF CHICAGO, ILLINOIS.

SPARK PLUG.

1,405,686.

Specification of Letters Patent. Patented Feb. 7, 1922.

Application filed February 16, 1920. Serial No. 359,094.

To all whom it may concern:

Be it known that I, THOMAS F. HANWAY, a citizen of the United States, and a resident of the city of Chicago, in the county of Cook and State of Illinois, have invented certain new and useful Improvements in a Spark Plug; and I do hereby declare that the following is a full, clear, and exact description of the same, reference being had to the accompanying drawings, and to the numerals of reference marked thereon, which form a part of this specification.

This invention relates to an improved form of spark plug wherein the central terminal or conductor extending through the insulating material of the plug, is split at its lower end and flares outwardly and with the outer or grounded terminals of the plug consisting of two substantially semicircular ring elements secured into the metal portion of the plug and encircling the flared ends of the central terminal, but out of contact therewith.

It is an object therefore of this invention to provide a spark plug wherein a multiplicity of spark points are provided so that fouling of any one or more of the terminal points cannot affect the sparking operation of others thereof, and also providing a means for producing a shower of sparks when all of the terminals function to permit the occurrence of sparks thereacross.

Other and further important objects of this invention will be apparent from the disclosures in the drawings and specification.

The invention (in a preferred form) is illustrated in the drawings and hereinafter more fully described.

Drawings.

Figure 1 is an elevation of a spark plug embodying the principles of my invention.

Figure 2 is a central vertical section taken therethrough with parts in elevation.

Figure 3 is a bottom plan view of the spark plug.

Figure 4 is an elevation of the central terminal of the spark plug.

Figure 5 is a fragmentary view partly broken away of the lower end of the plug.

Figure 6 is another fragmentary view partly broken away of the lower end of the plug.

Description.

The reference numeral 1 indicates a metal

casing or tubular member within which the parts of the spark plug are assembled. Said casing 1 is formed to afford a hexagonal nut 2 on its upper outer surface and at its lower portion of reduced diameter is threaded as indicated at 3 to permit attachment thereof into the spark plug aperture of an engine. Fitted into the tubular casing 1 is a porcelain or other insulating element 4 with a sealing gasket of copper or other suitable material disposed between plug element and the casing 1, and with a gland member 6 threaded into the upper portion of the tubular casing 1 and bearing downwardly upon the insulating element through another sealing gasket 7 to hold said element tightly and sealingly within the tubular casing 1. Said insulating element is cored out on its interior and has inserted therethrough upwardly through the lower end thereof, a conductor or central terminal member 8. The lower end of said terminal member 8 is enlarged as indicated by the reference numeral 9 and at a point below, is split into four portions which are bent outwardly each affording a prong-shaped spark terminal and denoted by the reference numeral 10. A sealing gasket 11 is fitted around the upper surface of the enlarged portion 9 to bear against the end of the recess in said insulating element 4 as clearly shown in Figure 2. At its upper end said central terminal member 4 is squared as indicated by the reference numeral 12 and thereabove is cylindrical and threaded as indicated by the reference numeral 13.

Owing to the peculiar shape of the cylindrical terminal element 4 it is preferable to mold the insulating element therearound so that the two become permanently associated.

As shown in Figure 2, engaged over the upper end of the terminal element 4 is a gasket or washer 14 and fitted over, and overlapping the upper end of the insulating element, and threaded on the central terminal 4, is a small clamping nut 15. A wire terminal fitting 16 is threaded on the upper threaded end of the terminal member 4 and bears downwardly against said nut 15. The lower face of the threaded portion 3 of the tubular casing 1 is apertured at two points with pairs of apertures diametrically oppositely disposed, and engaged therein are the bent ends 17 of semicircularly curved spark terminal members 18. Said terminal

members 18 encircle the outwardly flared spark terminals 10 and are spaced therefrom the proper spark-gap distance. The central terminal element 8 receives the ungrounded high-tension terminal of an ignition system connected thereto at the wire terminal fitting 16.

When the high-tension current is passed through said terminal 8, a shower of sparks 10 occurs between the spark terminals 10 and the spark terminals 18 which are connected in the metal portion or grounded parts of the spark plug. In the event that any of the spark gaps between any one of the terminals 10 and 18 become fouled so as to hinder the flashing of a spark thereacross, the necessary ignition spark will take place 15 across the other terminals 10 and 18. A copper gasket or washer 19 is provided to effect 20 a tight-fitting connection between the casing 1 and the engine to which the spark plug is attached.

I am aware that numerous details of construction may be varied through a wide

range without departing from the principles 25 of this invention, and I therefore do not purpose limiting the patent granted otherwise than necessitated by the prior art.

Claim.

30

In a spark plug, an inner electrode, a hollow metallic cylinder surrounding said electrode, and having holes parallel to the axis of said cylinder in the end thereof nearest the spark gap, and a circular outer electrode 35 comprising two semicircular wire members with their ends at an angle to the plane of the circle, said ends being seated in said holes and being of a length to support the circle with its plane through the end of the 40 inner electrode.

In testimony whereof I have hereunto subscribed my name in the presence of two subscribing witnesses.

THOMAS F. HANWAY.

Witnesses:

EARL M. HARDINE,
OSCAR HARTMANN.
